UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,825, dated March 21, 1882.

Application filed February 11, 1882. Term of patent 3½ years.

To all whom it may concern:

Be it known that I, HENRY HUNT, of Greenville, in the county of Hudson and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The ground *a* is filled in irregularly-shaped groups by small ornamental work, the different groups being made up of various small figures, including mural, etruscan, triangular, diamond-shaped, and other right-lined ornaments, and spiral, scroll, and other circular forms. On this groundwork are loosely scattered various flower groups.

A is a group consisting of the star-shaped flower-and-leaf cluster *B*, projecting downward, and the larger cluster *C* above, having a large rose and a rose-bud to the left, a central mass of flowers above, and to the right and above small bell-like flowers, all in a loose setting of leaves.

D is a blossoming leaf spray. *E* is a somewhat similar blossoming leaf spray. *F* is a leaf spray bearing two star-shaped flowers.

G is a large running group arranged along a common stem, beginning on the right with a large open rose and its leaf-setting, forming *H*; another rose-and-spray group below, *K*; in the center a group, *L*, of three rose-buds with leaves and three drooping leaf sprays below; and on the left a group, *M*—a half-open flower with leaves and buds below.

N is a small spray of circular flowers.

O, shown in part at each end of the photograph, is a small spray bearing four leaves.

P is a group, shown in part on each side and at each end of the photograph, and arranged along a common stem running horizontally toward the right and then upward. The horizontal portion of the stem, with the flowers and leaves immediately connected with it, forms the group *Q*, while the remainder of *P*, consisting of a rose opening to the left and open leaves below, forms the group *R*.

S is a small leaf-and-bud spray, somewhat similar to *D*.

I claim—

1. The design for carpets, consisting of the ground *a*, substantially as shown.

2. The design for carpets, consisting of the groups *A*, (including *B* and *C*), *D*, *E*, *F*, *G*, (including *H* *K* *L* *M*), *N*, *O*, *P*, (including *Q* and *R*), and *S*, substantially as shown.

3. The design for carpets, consisting of the groups *A*, (including *B* and *C*), *D*, *E*, *F*, *G*, (including *H* *K* *L* *M*), *N*, *O*, *P*, (including *Q* and *R*), and *S*, and ground *a*, substantially as shown.

4. The design for carpets, consisting of the group *A*, (including *B* and *C*), substantially as shown.

5. The design for carpets, consisting of the group *G*, (including *H* *K* *L* *M*), substantially as shown.

6. The design for carpets, consisting of the group *P*, (including *Q* and *R*), substantially as shown.

HENRY HUNT.
